UNITED STATES PATENT OFFICE.

JOHN C. MILLER AND EDWARD SCHMITZ, OF WATERBURY, CONNECTICUT, ASSIGNORS TO THE MATTHEWS & WILLARD MANUFACTURING COMPANY, OF SAME PLACE.

DESIGN FOR A LAMP-FOUNT HOLDER.

SPECIFICATION forming part of Design No. 23,671, dated October 2, 1894.

Application filed August 24, 1894. Serial No. 521,246. Term of patent 3½ years.

To all whom it may concern:

Be it known that we, JOHN C. MILLER and EDWARD SCHMITZ, of Waterbury, in the county of New Haven and State of Connecticut, have invented a new Design for Lamp-Fount Holders; and we do hereby declare the following, when taken in connection with the accompanying drawing and the letters of reference marked thereon, to be a full, clear, and exact description of the same, and which said drawing constitutes part of this specification.

The figure is a perspective view of a lamp fount holder, embodying our design.

Our invention relates to a design for lamp fount holders, and consists in the configuration and ornamentation as hereinafter described and shown in the accompanying illustration.

The body of our design is of bowl shape, its lower end contracted toward the base. The ornamentation consists of a series of substantially circular shields A, extending around the largest diameter of the bowl, and each of the shields is surrounded by four shell ornaments B. The space between the shell 25 ornaments B is filled by a large leaf-like ornamentation C. Below the shields the body is of lattice work D, merging at the lower ends into leaf ornamentations E and terminating in a plain ring F. The whole is surmounted 30 by two parallel bands G H, which are united by lattice work I.

We claim—

The design for a lamp fount holder, as herein described and shown. 35

In testimony whereof we have signed this specification in the presence of two subscribing witnesses.

JOHN C. MILLER.
EDWARD SCHMITZ.
